AUTOMATIC TRAIN-STOPPING MECHANISM.

1,157,144.

Specification of Letters Patent.

Patented Oct. 19, 1915.

Application filed December 28, 1914. Serial No. 279,240.

To all whom it may concern:

Be it known that I, WERNER BEUTEL, a subject of the Emperor of Germany, residing at Bridgeport, county of Fairfield, State of Connecticut, have invented an Improvement in Automatic Train-Stopping Mechanism, of which the following is a specification.

This invention has for its object to provide mechanism for use on locomotives, which is adapted in coöperation with a plurality of contact elements upon the road bed to stop a train automatically should the engineer fail to slow down at predetermined places or attempt to run past signals set against him.

With this and other objects in view I have devised the novel automatic train stopping mechanism which I will now describe, referring to the accompanying drawings forming a part of this specification and using reference characters to indicate the several parts.

Figure 1 is a view partly in elevation and partly in section illustrating the construction and operation of my novel invention, the operative parts being at their normal position and a portion of the locomotive being indicated in dotted outline; Fig. 2 a detail sectional view of the stopping cylinder and coöperating parts, as seen from the left in Fig. 1; Fig. 3 a detail sectional view of the stopping cylinder valve; Fig. 4 a view on an enlarged scale partly in elevation and partly in section, corresponding with Fig. 1, but showing the parts in the emergency stopping position, the stopping cylinder valve and its connections being removed for clearness; Fig. 5 a detail view partly in elevation and partly in section showing the emergency brake valve in its normal position; Fig. 6 a similar view showing the position of the emergency brake valve after its first actuation, and Fig. 7 is a diagrammatic view illustrating coöperating contact elements on the road bed and a signal.

I have illustrated my invention as applied to the straight air system of brake operating mechanism.

10 denotes the throttle lever and 11 a rod pivoted thereto, which operates as usual to control the supply of steam to the engine cylinders, not shown. The throttle lever is adapted to be operated by means of compressed air from a tank 12. A pipe 13 leads

from the tank to a chamber 14 in which a slide valve 15 operates to control the passage of air to throttle lever cylinder 16.

17 denotes a piston in said cylinder, 18 the piston rod and 19 a link having a rack and pawl connection 82 with the throttle lever. The slide valve is provided with a port 20 extending through it longitudinally and a peripheral recess 14; and is carried by a rod extending through the chamber at both ends. A spring 22 at one end of said rod acts normally to force the valve toward the right, as shown in Fig. 4. The opposite end of the rod is pivotally connected to a resetting lever 23 shown as pivoted on a bracket 24. Rod 21 carries a beveled disk 25 which is adapted to engage a shoulder 26 on a bell crank lever 27. A spring 28 acts to retain the bell crank lever in its normal position. When the piston and valve have been placed in the position shown in Fig. 4 by an emergency stop or slow-down, the engineer by operation of resetting lever 23, will move said parts to the position shown in Fig. 1. The bevel of the disk will engage an incline 29 on the bell crank lever and will swing said lever downward against the power of spring 28 until the disk has been carried past the shoulder, when the spring will cause the shoulder to lock the disk and valve rod in the position shown in Fig. 1 and in dotted lines in Fig. 4.

The operation of the slide valve and piston in effecting an emergency operation of the throttle lever will presently be described.

In Figs. 1, 2 and 7 I have shown contact elements consisting of slides 30 adapted to be reciprocated in suitable housings 31 upon the road bed by means of connections 32 which may or may not be operated in connection with a suitable signal, as 33, which indicates a signal of the semaphore type. Upon bridge and curve approaches, fixed contact elements may be used. The contact elements when in the operative position are adapted to be engaged by a stopping rod 34 carried by a stopping piston 35 and projecting through one of the heads of a stopping cylinder 36. A spring 37 under the piston acts to move it to the raised position, as indicated by dotted lines in Fig. 2. The cylinder has rigidly secured thereto arms 38 and is pivoted to a bracket 39 so as to oscillate thereon. Air is supplied to the stop-

ping cylinder by means of a pipe 40 which connects with pipe 13.

41 denotes slotted links connected to the outer ends of arms 38, their other ends being pivoted to a rod 42 adapted to slide in a bracket 43. A spring 44 bearing against the bracket and against a collar on the rod normally acts to retain the cylinder in a vertical position, as in Fig. 1. A chain 45 connects rod 42 with bell crank lever 27. Pipe 40 is provided with a stopping cylinder valve 46 having an arm 47 which is connected by means of a link 48 to the throttle lever. This valve is a three way valve (see Fig. 3 in connection with Fig. 1). The plug 83 is provided with a hole 84 through it which is adapted to align with pipe 40, and with a peripheral recess 85 which in the position shown in Fig. 3 is adapted to connect the stopping cylinder end of pipe 40 with a pipe 49 leading to the left end of throttle lever cylinder 16. A pipe 50 leads from pipe 13 to an engineer's brake valve 51, a pipe 52 leads from the brake valve to an emergency brake valve 53, a pipe 54 leads from pipe 50 to the emergency brake valve and a pipe 55 leads from the emergency brake valve to the brakes, not shown.

The emergency brake valve is a three way valve (see Figs. 5 and 6). The plug 56 is provided with a hole 57 through it, which is adapted to connect pipe 54 with pipe 55, and with a peripheral recess 58 which in the position shown in Fig. 5 connects pipe 52 with pipe 55. This plug has rigidly secured thereto exteriorly of the valve body, a ratchet 59 and an arm 60. A spring 61 connected to arm 60 and to a bracket 62 formed integral with or rigidly secured to the valve body acts to normally hold the plug in the position shown in Fig. 5, in which the air pressure of the tank passes through pipes 13 and 50 to engineer's brake valve 51 which is normally closed. When the engineer operates this valve, air passes through pipe 52 to emergency brake valve 53, which is normally in the position shown in Fig. 5 and through recess 58 in plug 56 and pipe 55 to the brakes.

63 denotes a bell crank lever and 64 an arm, both adapted to oscillate concentrically with plug 56.

65 denotes a spring controlled pawl which is socketed in bracket 62 and is adapted to engage the ratchet. This pawl is provided with a stem 66 having a slotted connection with a lever 67, which has its fulcrum on bracket 62. A chain 68 passing over one or more guide pulleys 69 connects resetting lever 23 with levers 67 and 63.

70 denotes a spring controlled pawl socketed in arm 64 and likewise engaging the ratchet. A link 71 has slotted connection with pawl 70 and with an arm of bell crank lever 62. It should be noted that when the

parts are in the position shown in Fig. 1, the resetting lever, chain 68, bell crank lever 63 and lever 67 will act to retain pawls 65 and 70 out of engagement with ratchet 59. This position of the pawls however is not shown in the drawings. Should the throttle lever be swung by the engineer to the closing position, not shown, piston 17 will not be moved, owing to the rack and pawl connection, but the plug of valve 46 will be swung by link 48 from a position in which the hole is aligned with pipe 40 to the position shown in Fig. 3. This permits air to pass from the stopping cylinder through pipe 49 to the left end of throttle lever cylinder 16, which is open to the atmosphere through a port 73 in the cylinder, a peripheral recess 74 in the slide valve and an exhaust port 75 in the cylinder, and spring 37 will raise the stopping piston and stopping rod out of the operative position. When the engineer again moves the throttle lever to the open position, as in Fig. 1, the plug of valve 46 will be again placed with the hole in alignment with pipe 40 and air under tank pressure will pass through pipes 13 and 40 to the stopping cylinder and force the stopping piston and stopping rod to the operative position against the power of spring 37, as in Figs. 1 and 2. Should the emergency brake valve be operated in the manner described, the slide valve will be moved from the position shown in Fig. 1 to that shown in Fig. 4. The effect will be to cut off the exhaust through port 73 and open an exhaust from the right end of the cylinder through a port 72, peripheral recess 74 and the exhaust port. Air under tank pressure will now pass through pipe 13, the slide valve and port 73 to the left end of the piston and will drive it to the position shown in Fig. 4. Air from the left end of the cylinder will also pass through pipe 49 to stopping cylinder valve 46 and will retain the pressure in pipe 40 and hold the stopping piston 35 and the stopping rod in operative position, as in Figs. 1 and 2.

The operation of the mechanism as a whole is as follows:—In Fig. 1 the parts of the emergency mechanism are in the normal position and the throttle lever in the open position. The hole in the plug of valve 46 is now held in alignment with pipe 40 (position not shown in the drawing) through the action of link 48 and the throttle lever. This permits air under tank pressure to pass through pipes 13 and 40 to stopping cylinder 36, and hold piston 35 down against the power of spring 37 and thus retain stopping rod 34 in position to engage a contact element on the road bed, in the present instance a slide 30, if in the stopping position. When the engineer stops the train or reduces speed by operation of the throttle lever, the effect will be to place valve 46 in

the position shown in Fig. 3. Air will now pass from stopping cylinder 36 through pipe 40 to valve 46 and will escape from said valve through pipe 49 and cylinder 16, and spring 37 will raise the stopping piston and rod out of operative position. Suppose now that contact elements are set against the train or it approaches a fixed contact element and the engineer fails to operate the throttle lever. When the stopping rod engages a contact element, the effect will be to oscillate the stopping cylinder and draw down one of the links 41, rod 42 and chain 45, which will cause bell crank lever 27 to be oscillated against the power of spring 28 and release disk 25 on valve rod 21 leaving spring 22 free to move slide valve 15 and the resetting lever from the position shown in Fig. 1 to the position shown in Fig. 4. It will be obvious from Fig. 1 in connection with Fig. 7 that the operation will be the same whether the locomotive is going forward or backward. When the slide valve is moved, as just described, air from the tank is cut off from port 72 and passes through the slide valve and port 73 to the left of piston 17 and drives it from the position shown in Fig. 1 to that shown in Fig. 4, and owing to the rack and pawl connection of link 19 with the throttle lever; moves the throttle lever toward the right (this position not being shown in the drawing) and shuts off steam from the locomotive cylinders, not shown. This movement of the throttle lever causes link 48 to again place the plug of valve 46 in the position shown in Fig. 3. The stopping piston and stopping rod cannot however be raised from the operative position by spring 37, for the reason that air under tank pressure will pass from the left end of throttle lever cylinder 16, through pipe 49, valve 46 and pipe 40 to the stopping cylinder and will retain the stopping piston and stopping rod in the operative position, as in Figs. 1 and 2. In the present instance I have shown three contact elements, see Fig. 7, the first of which in connection with the stopping piston and rod and parts coöperating therewith operates the throttle lever to shut off steam as described, and also through the operation of the slide valve, resetting lever, chain 68, bell crank lever 63 and lever 67 acts to set pawls 65 and 70 in engagement with the ratchet. The instant the stopping rod passes a contact element, spring 44 will act to return rod 42, links 41 and the stopping cylinder to their normal position, as in Fig. 1. The engagement of the stopping rod with the second contact element will again oscillate the stopping cylinder and draw down one of the links 41, rod 42 and chain 45, as before. This will cause an idle oscillation of bell crank lever 27 and will oscillate arm 64. As pawl 70 has already been set in engagement

with the ratchet, the movement of arm 64 will cause the pawl to carry ratchet 59 and valve plug 56 forward against the power of spring 61, pawl 65 sliding over the teeth of the ratchet and locking it against backward movement. The plug of the emergency brake valve is now in the position shown in Fig. 6, hole 57 in the plug being partly in alinement with pipes 54 and 55 so that air pressure from the tank can act through pipes 13, 50, 54 and 55 to start the operation of setting the brakes, but at a low pressure. An instant later the stopping rod will engage a third contact element (see Fig. 7 for the contact elements) the effect of which will be to throw the emergency brake valve to the fully open position, that is to place hole 57 in the plug in full alinement with pipes 54 and 55 so that full air pressure from the tank can act upon the brakes. It will thus be seen that the operation of my novel mechanism is first to shut off steam, second to partly open an emergency brake valve and cause air to pass to the brakes and third, to fully open the emergency brake valve and permit the full air pressure to act upon the brakes. It should be noted that the emergency operation in stopping a train is wholly automatic, that is, independent of any act of the engineer, and furthermore that should the engineer stop the train or slow down in the usual manner by operation of the throttle lever and the engineer's brake valve, the emergency mechanism will remain wholly inoperative.

After each operation of the emergency mechanism the parts are again placed in operative position by swinging resetting lever 23 from the position shown in Fig. 4 to that shown in Fig. 1. This movement of the resetting lever causes rod 21 to move the slide valve to the position shown in Fig. 1 against the power of spring 22. The instant the slide valve is placed in the position shown in Fig. 1, air from the chamber will pass through port 72 to the right of piston 17 and will move said piston toward the position shown in Fig. 1, air from the left of the piston exhausting through port 73.

In order to prevent the possibility of accidental movement of the throttle lever toward its opening position under any circumstances, as when the resetting lever is operated, I have provided a gravity catch 76 on the throttle lever which is adapted to engage a suitable keeper 77 which may be a fixed part with an eye, or a U or an L shaped fixed part. When the throttle lever is operated by my novel mechanism, as already described, that is swung over toward the right from the position shown in Fig. 1, the gravity catch will engage the keeper and lock the throttle lever in the 120_{aa} 125_{cc} 130_{aa}

shutting off position from which it can be moved only when the gravity catch is intentionally lifted out of engagement with the keeper. I have shown the gravity catch 5 as adapted to be released by a hand operated connection 78 on the throttle lever.

In order to provide an accurate count of all operations of my novel mechanism, whether through failure of the engineer to 10 act or from any other cause, I provide a counter 79 of any suitable construction, the shaft 80 of which is shown as actuated by means of a crank and link connection 81 with bell crank lever 27. This insures that 15 each automatic stoppage of the train will be made a matter of record for the consideration of the managing official.

Having thus described my invention I claim:

20 1. In a mechanism of the character described, the combination with a throttle lever, operating means therefor, an emergency brake valve, an oscillatable stopping cylinder, stopping piston and stopping rod, and 25 connections between the stopping cylinder and the emergency brake valve for opening said valve by successive steps, of means for supplying the throttle lever operating means and the stopping cylinder with air 30 under pressure, and connections between the throttle lever operating means and the stopping cylinder, engagement of the stopping rod with a plurality of contact elements 35 causing oscillation of the stopping cylinder and actuation of the throttle lever and emergency brake valve.

2. In a mechanism of the character described, the combination with an oscillatable stopping cylinder, stopping piston and 40 stopping rod, of a throttle lever, an emergency brake valve, intermediate connections between the stopping cylinder and the emergency brake valve whereby oscillation of the cylinder will actuate said valve, and 45 pressure operated means controlled by said cylinder for actuating the throttle lever.

3. In a mechanism of the character described, the combination with an oscillatable stopping cylinder, a stopping piston and 50 stopping rod, a plurality of contact elements adapted to be engaged by the stopping rod and means for supplying air under pressure to said cylinder to retain the piston and rod in the engaging position, of an 55 emergency brake valve, operating means therefor and connections intermediate the stopping cylinder and said operating means for progressively actuating the emergency 60 brake valve when the stopping cylinder is oscillated by the contact elements.

4. In a mechanism of the character described, the combination with an oscillatable stopping cylinder, stopping piston and 65 stopping rod, and means for supplying air under pressure to said cylinder to retain

the piston and rod in the engaging position, of an emergency brake valve, connections intermediate said valve and the stopping cylinder, and a plurality of contact elements adapted to be engaged by the stopping rod, successive engagements of the stopping rod with contact elements partly opening and then fully opening said valve. 70

5. In a mechanism of the character described, the combination with an oscillatable stopping cylinder, stopping piston and stopping rod, and means for supplying air under pressure to the cylinder to retain the piston and rod in the engaging position, of a throttle lever, an emergency brake valve, 75 connections intermediate the stopping cylinder and the throttle lever and emergency brake valve, and a plurality of contact elements adapted to be engaged by the stopping rod, whereby successive engagements 80 of the stopping rod with contact elements will actuate the throttle lever, partly open and then fully open the emergency brake valve. 85

6. In a mechanism of the character described, the combination with an oscillatable stopping cylinder, stopping piston and stopping rod, and means for supplying air under pressure to the cylinder to retain the piston and rod in the engaging position, of an 90 emergency brake valve having a plug with a hole through it, a ratchet fixed to said plug, a bell crank lever, an arm adapted to oscillate concentrically with the plug, a bracket, a spring controlled pawl socketed 100 in the bracket and engaging the ratchet, a spring controlled pawl in the oscillating arm, a link connecting the last mentioned pawl with the bell crank lever, a lever to which the first mentioned pawl is attached, 105 connections with the last mentioned lever and the bell crank lever to normally retain the pawls out of engagement with the ratchet, said connections controlled by the stopping cylinder, connections intermediate 110 the oscillating arm and the stopping cylinder, a plurality of contact elements adapted to be engaged by the stopping rod and connections for air under pressure with said valve, whereby successive engagements of 115 the stopping rod with contact elements will first set the pawls in engagement with the ratchet and then cause the oscillating arm to partly open and then fully open the valve. 120

7. In a mechanism of the character described, the combination with an oscillatable stopping cylinder, stopping piston and stopping rod, and means for supplying air under pressure to the cylinder to retain the piston and rod in the engaging position, of an 125 emergency brake valve having ratchet connections, a resetting lever having connections with said valve, by which said valve may be returned to its normal position after operation, connections intermediate the stop- 130

ping cylinder and the ratchet connections, and a plurality of contact elements adapted to be engaged by the stopping rod whereby oscillation of the stopping cylinder will cause the emergency brake valve to open with successive steps.

8. In a mechanism of the character described, the combination with an oscillatable stopping cylinder, stopping piston and stopping rod, and means for supplying air under pressure to the cylinder to retain the piston and rod in the engaging position, of a throttle lever, pressure operated means controlled by the cylinder for actuating the throttle lever, a resetting lever, an emergency brake valve, connections intermediate said resetting lever and valve, other connections intermediate said valve and the stopping cylinder, and contact elements adapted to be engaged by the stopping rod.

9. In a mechanism of the character described, the combination with an oscillatable stopping cylinder, stopping piston and stopping rod and means for supplying air under pressure to the cylinder to retain the piston and rod in the engaging position, of an engineer's brake valve, a three-way emergency brake valve, a passage for air leading from the engineer's brake valve and normally passing through the emergency brake valve, and connections operated by the stopping cylinder for opening the emergency brake valve and closing the passage therein from the engineer's brake valve.

10. In a mechanism of the character described, the combination with an oscillatable stopping cylinder, stopping piston and stopping rod and means for supplying air under pressure to the cylinder to retain the piston and rod in the engaging position, of a throttle lever, an engineer's brake valve, an emergency brake valve, a passage for air leading from the engineer's brake valve and normally passing through the emergency brake valve, and connections operated by the stopping cylinder for actuating the throttle lever, opening the emergency brake valve and closing the passage therein from the engineer's brake valve.

11. In a mechanism of the character described, the combination with an oscillatable stopping cylinder, stopping piston and stopping rod and means for supplying air under pressure to the cylinder to retain the piston and rod in the engaging position, of a throttle lever, a resetting lever, an engineer's brake valve, an emergency brake valve, a passage for air leading from the engineer's brake valve and normally passing through the emergency brake valve, connections to the throttle lever and the emergency brake valve operated by the stopping cylinder, and connections to the emergency brake valve operated by the resetting lever for returning the parts to their normal position.

12. In a mechanism of the character described, the combination with an oscillatable stopping cylinder, stopping piston and stopping rod and means for supplying air under pressure to the cylinder to retain the piston and rod in the engaging position, of a throttle lever, an engineer's brake valve, an emergency brake valve, a passage for air leading from the engineer's brake valve and normally passing through the emergency brake valve, a stopping cylinder valve, a connection between said valve and the throttle lever, whereby when the throttle lever is manually placed in the shutting-off position, air to the stopping cylinder is shut off, and connections to the throttle lever and the emergency brake valve operated by the stopping cylinder, whereby when the stopping cylinder is oscillated the throttle lever is actuated, the emergency brake valve opened and the passage therein from the engineer's valve closed.

13. In a mechanism of the character described, the combination with an oscillatable stopping cylinder, stopping piston and stopping rod and means for supplying air under pressure to the cylinder to retain the piston and rod in engaging position, of a throttle lever, an emergency brake valve, pressure operated means controlled by the stopping cylinder for moving the throttle lever to the shutting-off position, connections from the stopping cylinder adapted to open the emergency brake valve, and a catch and keeper for locking the throttle lever in the shutting-off position.

14. In a mechanism of the character described, the combination with an oscillatable stopping cylinder, stopping piston and stopping rod and means for supplying air under pressure to the cylinder to retain the piston and rod in the engaging position, of a throttle lever, an emergency brake valve, pressure operated means controlled by the stopping cylinder for moving the throttle lever to the shutting-off position, connections from the stopping cylinder adapted to open the emergency brake valve, a counter and connections actuated by the stopping cylinder each time the automatic stopping mechanism is operated.

15. In a mechanism of the character described, the combination with an emergency brake valve, an oscillatable stopping cylinder, stopping piston and stopping rod and a contact element, of air connections for normally retaining the stopping piston and rod in the engaging position, a spring actuated slide valve for controlling the air pressure, a spring for retracting said piston and rod when the pressure is relieved, connections with the stopping cylinder for controlling the slide valve and other air connections controlled by the slide valve for retaining the stopping piston and rod in the

engaging position when the stopping cylinder has been oscillated by engagement of the stopping rod with a contact element.

16. In a mechanism of the character described, the combination with a contact element, of an oscillatable stopping cylinder having a stopping piston and a rod adapted to engage the contact element, air connections with the cylinder for retaining the stopping piston and rod in the engaging position, a spring for retracting the stopping piston and rod when the air pressure is removed, connections with the stopping cylinder for controlling the air pressure, and other air connections controlled by the stopping cylinder for retaining the stopping piston and rod in the engaging position when the stopping cylinder has been oscillated by engagement of the stopping rod with a contact element.

17. In a mechanism of the character described, the combination with a contact element, of an oscillatable stopping cylinder, a stopping piston and a rod adapted to engage the contact element, air connections with the cylinder for retaining the stopping piston and rod in the engaging position, means for retracting the stopping piston and rod, and other air connections controlled by the stopping cylinder for retaining the stopping piston and rod in the engaging position when said cylinder has been oscillated by engagement of the stopping rod with a contact element.

18. In a mechanism of the character described, the combination with a contact element, of a throttle lever, a spring actuated slide valve for controlling the operation of said lever, an oscillatable stopping rod adapted to engage the contact element, means for holding the slide valve against movement, connections with the stopping rod to release the slide valve, air connections controlled by the throttle lever for retaining the stopping rod in the engaging position and for releasing the same, means for retracting said rod, and other air connections controlled by the slide valve for retaining said rod in the engaging position when said rod has been oscillated by engagement with a contact element.

19. In a mechanism of the character described, the combination with a contact element, of a throttle lever, air connections for operating the throttle lever, a spring actuated slide valve for controlling the air connections, an oscillatable stopping cylinder, a stopping piston, a stopping rod carried thereby and adapted to engage the contact element, connections intermediate the stopping cylinder and the slide valve, air connections controlled by the throttle lever for retaining the stopping piston and rod in the engaging position and for releasing the same, a spring for retracting said

piston and rod, and other air connections controlled by the slide valve for retaining the stopping piston and rod in the engaging position when the stopping cylinder has been oscillated by engagement of the stopping rod with a contact element.

20. In a mechanism of the character described, the combination with a contact element, an oscillatable stopping cylinder, a stopping piston carrying a stopping rod adapted to engage said element, a throttle lever and an emergency brake valve, of air connections with said cylinder for retaining the stopping piston and rod in engaging position, air controlled means for actuating the throttle lever, connections intermediate the stopping cylinder and the emergency brake valve, and connections with the stopping cylinder for controlling said air controlled means, whereby engagement of the stopping rod with a contact element will cause operation of the throttle lever and opening of the emergency brake valve.

21. In a mechanism of the character described, the combination with a contact element, an oscillatable stopping cylinder, a stopping piston carrying a stopping rod adapted to engage said element, a throttle lever, an emergency brake valve, and connections intermediate the emergency brake valve and the stopping cylinder, of air connections for normally retaining the stopping piston and rod in the engaging position, a spring actuated slide valve for controlling the throttle lever, means for retracting the piston and rod when the throttle lever is operated manually, connections with the stopping cylinder for controlling the slide valve, and other air connections controlled by the slide valve for retaining the stopping piston and rod in the engaging position when the stopping cylinder is oscillated by engagement of the stopping rod with a contact element.

22. In a mechanism of the character described, the combination with a contact element, an oscillatable stopping cylinder, a stopping piston carrying a stopping rod adapted to engage said element, and a throttle lever, of a throttle lever cylinder, a spring actuated slide valve, air connections controlled by the throttle lever for normally retaining the stopping piston and rod in the engaging position, means for retracting said piston and rod when the throttle lever is operated manually, connections with the stopping cylinder for controlling the slide valve, and other air connections intermediate the throttle lever cylinder and the stopping cylinder for retaining the stopping piston and rod in the engaging position when the slide valve is operated by oscillation of the stopping cylinder.

23. In a mechanism of the character described, the combination with an emergency

brake valve, an oscillatable stopping cylinder, a stopping piston and rod and a contact element, of a throttle lever, a throttle lever cylinder, a spring actuated slide valve controlling the pressure in said cylinder, air connections controlled by the throttle lever for normally retaining the stopping piston and rod in the engaging position, connections with the stopping cylinder for controlling the slide valve, and other air connections intermediate the throttle lever cyl-

inder and the stopping cylinder for retaining the stopping piston and rod in the engaging position when the slide valve is operated by oscillation of the stopping cylinder. 15

In testimony whereof I affix my signature in presence of two witnesses.

WERNER BEUTEL.
